UNITED STATES PATENT OFFICE.

GERARD BEEKMAN, OF NEW YORK, N. Y.

BACK-PEDALING BRAKE.

SPECIFICATION forming part of Letters Patent No. 609,651, dated August 23, 1898.

Application filed August 31, 1897. Serial No. 650,108. (No model.)

To all whom it may concern.

Be it known that I, GERARD BEEKMAN, a citizen of the United States, and a resident of the city, county, and State of New York, have invented certain new and useful Improvements in Propelling and Braking Mechanism for Cycles, of which the following is a specification.

My invention relates to improvements in bicycle propelling and braking mechanism operated by simultaneous depression of two opposite rotary pedal-cranks within the principle embodied in my device made the subject of Letters Patent No. 550,938, dated December 10, 1895, the rotary motion of the cranks being imparted to the sprocket-wheel or other driven element by frictional engagement determined by foot-pressure. A clutch action is produced intermittently by the pressure or impulses of the rider's feet upon the pedals, and forward or backward propulsion, or braking, or coasting may each be effected according to the manner of moving or arresting the pedal-cranks and without requiring the feet to be removed from them. By a reduction or release of foot-pressure the pedals may remain stationary or be revolved at a slower speed than the revolution of the sprocket-wheel or driven element, and the propelling impulses may be exerted at such intervals as desired, permitting the rider to rest or dwell between impulses at will, and he may thereby use a comparatively "low gear," giving advantage in hill-climbing, while not imposing a continuous and tedious rapidity of revolution of the cranks when speeding rapidly on level or descending roads.

My invention especially relates to improvements in mechanism such as shown and described in my separate patent application, Serial No. 632,282, filed April 15, 1897, wherein a clutch is used having its engaging and disengaging movements in the length of the crank-shaft or axis and having such movements imparted by foot-pressure through the agency of cam formations, which expand the crank-hubs from one another and bind the clutch-surfaces, which mechanism may be used in combination with positive clutches.

The object of my present invention is to improve the general construction of the machine.

My invention consists in certain constructive features hereinafter fully described and claimed.

Referring to the drawings, Figure 1 represents a central vertical longitudinal sectional view of my improved bicycle propelling and braking mechanism, showing the internal construction of the parts. Fig. 2 is a vertical cross-section taken at $\alpha\alpha$, Fig. 1. Fig. 3 is a detail view of the crank-shaft clutch parts in side elevation. Fig. 4 is an end view of Fig. 3, partly in section. Fig. 5 is a side view of one of the crank-hubs and a portion of the shaft integral therewith. Fig. 6 is a detail view of the clutch-pieces, partly in section, on the line yy , Fig. 2. Fig. 7 is a similar view showing a modification. Fig. 8 is a longitudinal sectional view of the crank-shaft, showing a modification.

The cranks A A' have their hubs 1 2 and integral shaft portions 3 4 securely fixed into the clutch parts 5 6 by means of tongues and mortises 30 31, forming relatively movable shaft-sections B B', and both said sections revolve together except for a slight yielding motion rotatively with respect to one another, which is converted into longitudinal motion, limited by the contact of the faces 5 6 of said sections with the rigidly-coupled concave clutch portions 7 8, respectively, of the driven element or shaft C of the sprocket-wheel D. The part C is mounted on ball-bearings 9 10, and the crank-shaft B B' is journaled at its extremities 3 4 in the extremities of the said shaft C. When the cranks A A' are propelling, the parts B B' revolve with the part C, and the ball-bearings 9 10 therefore serve for the crank-shaft B B'. By thus making the cranks A A' and their hubs 1 2 separable from the clutch parts 5 6 these clutch parts may in case of wear be easily replaced.

The slight rotative movement of the shaft-sections B B' with respect to one another (in response to the simultaneous depression of the pedals of the opposite cranks A A') is converted into a longitudinal movement by the expanding action of the cam formations or V-shaped recesses 11 12 upon the interposed frusta-conic rollers 14, and such action is opposed by a spring arrangement consisting of a compression-spring, such as E or E', or E² in Fig. 8, confined under pressure

between the hubs 1 2 and the head 16 of the screw-threaded tie-rod 17 and screw-nut 18 on said tie-rod, respectively. When at rest, the resistance of the compression-spring is taken up on the pieces 14, in order that the 5 pedals when relieved from pressure may readily return to their normal position. The spring may be adjusted by means of the nut 18 and jam-nut 19 with sufficient force to resist the weight of the rider's feet on the 10 pedals, it being intended that the frictional clutch device shall engage only when depression is effected by transferring the weight of the 15 rider's body more or less from the saddle to the pedals, assisted in emergency by muscular effort.

The relative limited rotative movement of the shaft-sections B B' under the longitudinal pressure of the springs may be comparatively relieved from friction by the interpolation of ball-bearings, such as F in Fig. 8, which figure also illustrates a concentrated arrangement of the springs at E². The bearing-cone 40 slides upon the tie-rod 17, and 20 the bearing-cup 41 rests against the shoulder 42 in the shaft-section B. For the frustaconic rollers 14, Figs. 1 and 2, may be substituted blocks 45, Fig. 7, which by diagonal action separate the sections 5 6 when the 25 pedals are simultaneously depressed. In Fig. 30 6 the action is that of a screw of limited motion upon interposed friction-rollers, while in Fig. 7 it is that of a block moving with precision on the hinges 45^a, the blocks 45 being 35 arranged about the shaft in locations corresponding to the rollers 14 in Fig. 2.

In addition to the friction clutch device 5 7 and 6 8 I prefer to also employ a positive clutch for forward propulsion, consisting of 40 rollers 20, arranged in inclined pockets 21, which for the purpose of concentration are located in the surfaces 5 6 of the clutch-sections and are inclined to the axis of rotation, 45 said rollers having sufficient weight to engage through gravity without lost motion on either surface 7 8 of the part C when the crank A or A' is forwardly propelled. The inclined pockets 21 will support the balls or rollers 20 with their axes of rotation inclined 50 to the axis of rotation of the driving members. The power of the device as a brake can be determined by varying the angle of construction of the conical friction-surfaces 5 6 7 8 and the formation of the recesses 11 12 55 and pieces 14.

In the operation of the device the driving element, consisting of parts A B A' B', is normally disengaged rotatively from the driven element C D. In order to start the bicycle 60 forwardly, foot-pressure is applied to the pedal of the forwardmost crank, and the roller-clutch 20 at once engages with the sprocket-wheel hub or shaft C and drives the machine. When headway is obtained, the 65 rider may relax his foot effort at pleasure between strokes, exerting a thrust as occasion requires, and thereby avoid continuous rapid

motion of the feet when running at high speed on level roads or under other conditions requiring moderate effort to keep the machine 70 in motion at the desired speed. In order to coast or allow the bicycle to run for a distance by its momentum, the pedals may be brought to rest, the shaft B B' remaining idle within the revolving hollow shaft or hub 75 C, and the springs E E', (or E²), supporting the weight of the feet through the agency of the expanding devices described, affording a comfortable foot-rest without necessitating the removal of the feet from the pedals. 80 Whenever it is desired to moderate or check the speed of the wheel, the weight of the rider may be more or less transferred from the saddle to the pedals, simultaneously rotating the cranks A A' and their respective shaft-sections B B' in opposite directions to the slight extent limited by the impingement of the clutch-surfaces 5 7 and 6 8 applying the desired degree of frictional retardation to the revolving part C. An emergency stop may 90 be effected in like manner by a vigorous depression of the pedals produced by a combination of the weight of the rider and muscular effort. Braking thus takes the place of back-pedaling as ordinarily understood. 95 The cycle may also be propelled without a complete revolution of the pedal, and for exhibition purposes, &c., may be propelled backward by simultaneously depressing both pedals and applying the excess of pressure to 100 the rear pedal. In other words, entire control and management of the machine are obtained by the action of the feet on the pedals above described. The use of the weight of the rider for braking as a substitute for the 105 muscular effort of back-pedaling as ordinarily practiced and the relief from the necessity of following the motion of the machine on the pedals when propulsion is not required make the device a labor-saver. 110

It will be observed that two independent positive clutches are provided by my improvements above described, said clutches comprising two groups of rollers or balls arranged in seats between the friction-clutch faces of 115 the driven element and two members of the driving element, the seats for the balls or rollers being inclined to the axis of rotation.

The mechanism thus described is concentrated within the crank-shaft hanger G, preserving the conventional form of the bicycle-frame. 120

Having thus fully described my invention, what I claim, and desire to secure by Letters Patent, is—

1. In a cycle, the combination of a driven element a driving element consisting of two members, having a limited relative longitudinal and rotary movement, coöperating friction-faces upon the driven element and the 130 two relatively movable members of the driving element, and two independent positive clutches comprising two sets or groups of rollers or balls arranged in seats between the

- friction-clutch faces, one set or group being arranged between each member of the driving element and the driven element, substantially as set forth.
- 5 2. In a cycle, the combination of a driven element, a driving element consisting of two members, having a limited relative longitudinal and rotary movement, coöperating inclined friction-faces upon the driven element and the two members of the driving element, and two independent positive clutches comprising two sets or groups of rollers or balls arranged in seats between the friction-clutch faces, which seats are inclined with reference to the axis of rotation, and one set or group being arranged between each member of the driving element and the driven element, substantially as set forth. 30
- 10 3. In a cycle, the combination of a driven element, a driving element consisting of two members, which have a limited relative movement, coöperating inclined friction-faces upon the driven element and the two members of the driving element which are thrown into engagement by the relative movement of the two members of the driving element, and two independent clutches comprising two sets or 35
- 15 4. In a cycle, the combination with a friction-clutch having its members respectively connected with the driving and driven elements, of rotary pedal-crank having a limited relative movement to actuate said clutch, a tie-bolt or axis and a spring confined upon the axis and tending to maintain said cranks normally in opposite relation, a bearing-cone 40 sliding on the axis and engaged by the spring, and rolling bearings between the bearing-cone and a bearing on one of the crank-hubs 45 to receive the pressure of said spring and relieve the cranks from friction in their said relative movement, substantially as set forth.
- Signed at the city, county, and State of New York this 24th day of August, A. D. 1897.
- GERARD BEEKMAN.
